Emmett M. Dunlap
INVENTOR

BY Victor J. Evans
ATTORNEY

UNITED STATES PATENT OFFICE.

EMMETT M. DUNLAP, OF SAN PEDRO, CALIFORNIA.

FLY BOOK.

Application filed November 27, 1922. Serial No. 603,564.

To all whom it may concern:

Be it known that I, EMMETT M. DUNLAP, a citizen of the United States, residing at San Pedro, in the county of Los Angeles and State of California, have invented new and useful Improvements in Fly Books, of which the following is a specification.

My present invention has reference to a fly or tackle receptacle for fishermen's use.

10 My primary object is to produce a device of this character in which a great number of flies may be arranged in a small case or receptacle to afford instantaneous selection of any one of the flies without necessitating the turning of leaves, as is common in the book form of such devices.

20 A further object is to produce a device of this character in which a suitable covered case which has arranged therein any desired number of rows of tubes separated from each other by pads, said case having its outer face at its upper end partly open whereby an inspection of the flies in any of the tubes and an instantaneous selection of a 25 desired fly may be readily obtained, the said case being also provided on its outer face with a bellows-like pocket in which leaders, etc. may be carried.

30 The drawing which accompanies and forms part of this application illustrates a satisfactory embodiment of the improvement reduced to practice, and wherein:

Figure 1 is a front elevation of the improvement.

35 Figure 2 is a sectional view approximately on the line 2—2 of Figure 1.

Figure 3 is a sectional view on the line 3—3 of Figure 2.

40 Figure 4 is a sectional view approximately on the line 4—4 of Figure 1.

The case 1 may be made of any desired material that is water-proof, and as disclosed by the drawing is in the nature of a rectangular member whose upper end is 45 open. The outer face of the case has its upper end disposed a considerable distance below the upper end of the back of the case so that the outer face of the case is thus partly open, the purpose of which will presently be apparent. In the case there are

preferably removably secured by a cord or the like any desired number of longitudinally arranged vertically disposed tubes 2. The rows of tubes are separated by any desired number of pads 3.

55 On its outer face the case is provided with a bellows-like pocket or pockets 4 which opens at its upper end and which is designed for the reception of leaders, etc.

Hinged, preferably through the medium 60 of a strap 5 to the back of the case 1 there is the flanged closure 6 of the improvement. The closure has its outer face provided with a fastening element 7 designed for engagement with a coacting member 8 on the outer 65 face of the receptacle.

The flies are arranged in the tubes and it will be apparent that upon opening the cover 6 the said flies may be instantly inspected so that the size and pattern desired 70 may be likewise instantly selected.

75 My improvement entirely overcomes the necessity of turning leaves and losing flies in streams of water, as is common with the well-known device for this purpose. The cover may be opened by simply laying the device upon the angler's lap, and the guts will remain straight in the tubes so that the crimping or twisting thereof will be entirely obviated.

80 Having described the invention, I claim:

1. In an article for the purpose set forth, a case having its front partly open at the mouth thereof, tubes arranged in rows in 85 the case, compressible pads spacing the rows of tubes, a cover loosely hinged to the back of the case, and means for latching the cover on the case.

2. In an article for the purpose set forth, 90 a case having its front partly open at the mouth thereof, tubes arranged in rows in the case, compressible pads spacing the rows of tubes, a bellows-like pocket on the front of the case, a flanged cover loosely hinged 95 to the back of the case, and means for latching the cover on the case.

In testimony whereof I affix my signature.

EMMETT M. DUNLAP.
